COMBINED MOBILE LOG CARRIER AND BAR

Milton D. Hatfield, 1204 Roseway SE.,
Warren, Ohio 44484

Filed Jan. 16, 1973, Ser. No. 324,090

Term of patent 14 years

Int. Cl. D12—02

U.S. Cl. D12—29

FIG. 2.

FIG. 3

FIG. 1 is a perspective view of a combined mobile log carrier and bar showing my new design;

FIG. 2 is a perspective view thereof showing the side opposite that shown in FIG. 1;

FIG. 3 is a fragmentary perspective view thereof showing the bar shelf in upright position; and

FIG. 4 is a longitudinal sectional view taken along line 4-4 of FIG. 1.

I claim:

The ornamental design for a combined mobile log carrier and bar, substantially as shown and described.
